GOLF SHOE SPIKE

Mitchell J. Zaleski and Robert L. Richards,
Chicago, Ill.

Application May 5, 1949, Serial No. 91,544

6 Claims. (Cl. 36—59)

1

The present invention relates to golf shoes and is concerned primarily with the spikes which ordinarily are carried by the sole of such a shoe.

In the playing of the now popular game of golf, shoes which carry spikes are ordinarily worn so as to afford to the wearer a firm gripping engagement with the ground. Such spikes ordinarily project beneath the exposed surface of the sole so as to penetrate the turf on which the wearer is standing. Just so long as a player continues to tread on soft turf no particular hardship is encountered due to the presence of these spikes. However, as a player walks over the golf course he often steps on rocks and hard packed surfaces and on those occasions the now conventional spikes constitute a serious menace to the player's well being and disposition in that an appreciable shock or jar is transmitted through the spike to the wearer's foot.

With the spikes now available, the force of such shocks and jars are transmitted through a direct unyielding path from the spike to the shoe.

With the foregoing conditions in mind, the present invention has in view as its foremost objective, the provision of a spike for golf shoes which includes a yielding element which is adapted to function as a shock absorber, and thereby greatly minimize these shocks and jars which are transmitted to the wearer when he walks over hard surfaces.

More in detail, the invention has as an object, the provision of a spike assembly for golf shoes which consists essentially of a main plate having a threaded tubular stem for anchoring the same to the sole of a golf shoe. Received in the tubular stem of this plate is the shank of a spike and the latter carries an auxiliary plate that is spaced from the main plate. Interposed between the main and auxiliary plates is a rubber washer which is adapted to function as a shock absorber and which permits of a certain amount of play or movement between the respective plates.

A somewhat more detailed object of the invention is the provision, in a golf spike assembly of the type noted, of novel means for securely anchoring the main plate aforesaid in position on the shoe sole. In carrying out this object, the face of this plate which engages the sole carries a serrated peripheral rim, the teeth of which bite into the sole to afford a good anchorage.

Another object of the invention is to provide a modified form of golf spike assembly in which there is no interlock between the main plate and the auxiliary or spike plate other than the rubber cushion which is permanently bonded to the two.

Still another object of the invention is to provide a further modification in which the main plate aforesaid carries on its peripheral edges, fingers which interlock with the auxiliary or spike

plate and hold the latter and rubber cushion in assembled relation.

Various other more detailed objects and advantages of the invention such as arise in connection with carrying out the above noted ideas in a practical embodiment will, in part become apparent, and in part be hereinafter stated as the description of the invention proceeds.

The invention, therefore, comprises a spike for golf shoes which consists essentially of a main plate that is anchored to the shoe sole, an auxiliary or spike plate which carries the spike, a rubber cushion which is interposed between these plates, and means for maintaining the assembled relation of the plates and rubber cushion.

For a full and more complete understanding of the invention, reference may be had to the following description and accompanying drawing wherein:

Figure 1 is a view in side elevation of a spike for golf shoes designed in accordance with the precepts of this invention.

Figure 2 is a bottom plan view of the spike shown in Figure 1.

Figure 3 is a vertical section through the assembly of Figure 1 being taken about on the plane represented by the line 3—3 of Figure 1.

Figure 4 is a vertical section comparable to Figure 3 of a modification.

Figure 5 is a view in side elevation of another modification; and

Figure 6 is a section through a portion of a golf shoe depicting the manner in which one of the spikes of this invention is secured thereto.

Referring now to the drawing wherein like reference characters denote corresponding parts, and first more particularly to Figure 1, 2, and 3. A spike for golf shoes which is designed in accordance with the precepts of this invention is shown as consisting of the assembly of parts illustrated. This assembly is made up of the following elements: a main plate M, an auxiliary or spike plate A, a rubber cushion C, and a spike S.

The main plate M consists of a circular disc of metal having a lower face at 10 which engages the cushion C. Extending around the periphery of this disc on the face opposite to the face 10 is a rim 11 which is serrated as represented at 12. Upstanding from the central portion of the

main plate M is a tubular sleeve 13 which is exteriorly threaded as shown at 14. These threads 14 are intended to be screwed into a metal ferrule which is shown at 15 in Figure 6, and which are ordinarily included in the soles of golf shoes.

The serrations 12 are intended to bite into the exposed lower face of the sole such as shown at 16 in Figure 6.

The cushion C is of a washer like construction that is defined by a rubber pad which is formed with a central opening at 17 which aligns with

the bore of the sleeve 13. The upper face of this cushion C engages the face 10 of the plate M while the opposite face engages the inner face of the auxiliary or spike plate A.

The spike plate A is also of a washer like construction defined by a central opening 17 which is in alignment with the opening 11. The spike S has a shank 19 which passes through the aligned openings 17 and 18 and the bore of the sleeve 13. The upper end of this shank 19 is peened or riveted as indicated at 20 with the enlarged portion engaging the free end of the sleeve 13. The opposite end of the shank 19 carries the spike point 21 which terminates at a flange 22 which bears against the plate A.

Referring now more particularly to Figure 6, it will be noted that the conventional golf shoe ordinarily includes an outer sole 23 and an inner sole 24. This outer sole 23 is provided with an appropriate number of openings 25, each of which is lined with a metal ferrule 15 with the bore of the ferrule threaded. A number of the above described spikes which corresponds to the number of openings 25 is assembled on the sole 23 by screwing each threaded sleeve 13 into the respective ferrule 15 and continuing the screwing action until the serrations 12 are firmly imbedded in the exposed surface 16. In so positioning the spikes, an appropriate tool such as a wrench may be employed in conjunction with the recesses shown at 9 which are formed in the spike plate A. It will be noted that in this assembled relation, the head 20 of the spike shank 19 is spaced below the inner sole 24 to accommodate a certain amount of movement on the part of the shank and plates A and M.

Thus, when the wearer of one of these golf shoes treads on a hard surface, shocks and jars are taken up by the rubber cushion C.

Figure 4 illustrates one modification. In this form of the invention, the spike comprises three main parts; namely, a main plate M1, an auxiliary or spike plate A1, and a rubber cushion C1. The main plate M1 is of a disc shaped construction and upstanding from the central portion thereof is a solid threaded stud 26 which is adapted to be screwed into one of the ferrules 15. The auxiliary plate A1 has a shape corresponding to the plate M1 and extending downwardly from the central portion thereof is the spike element 27. The rubber cushion C1 is permanently bonded to the plates M1 and A1 as by vulcanization or by using an appropriate adhesive cement.

Figure 5 illustrates another modification in which the spike is made up of a main plate M2, an auxiliary or spike plate A2, and a rubber cushion C2. The main plate M2 takes the form of a flat disc from which upstands a threaded stud 28. The plate A2 is another flat disc carrying a spike element 29. The cushion C2 is interposed between the plates M2 and A2 and integrally joined to the peripheral edge of the plate M2, are a plurality of fingers 30 which extend downwardly over the edges of the cushion C2 and plate A2. Each of these fingers 30 is formed with an inturned flange 31 which engages the lower face of the plate A2 and establishes the interlock which maintains the parts assembled.

Each of the forms of invention shown in Figures 4 and 5 is assembled with the sole of a golf

shoe in the manner above described in connection with the form of invention depicted in Figure 6.

While preferred specific embodiments of the invention are hereinbefore set forth, it is to be clearly understood that the invention is not to be limited to the exact constructions, mechanisms and devices illustrated and described because various modifications of these details may be provided in putting the invention into practice within the purview of the appended claims.

What is claimed is:

1. A spike for a golf shoe comprising, in combination: a main plate, means carried by said plate for securing said plate to the sole of a golf shoe, an auxiliary plate, a spike element carried by said auxiliary plate, and a rubber cushion interposed between said plates.

2. A spike for a golf shoe comprising, in combination: a main plate consisting of a circular disc having a threaded sleeve extending outwardly from one face thereof, a rubber cushion engaging the face of said plate opposite to that from which said sleeve extends, and having an opening in alignment with the bore of said sleeve, a spike plate engaging the other face of said washer and having an opening in alignment with the said opening in said cushion, and a spike having a shank extending through said aligned openings in the bore of said sleeve, and carrying a spike element projecting below said spike plate.

3. A spike for a golf shoe comprising, in combination: a main plate consisting of a circular disc having a threaded sleeve extending outwardly from one face thereof, said plate having an annular rib formed with radial serrations, a rubber cushion engaging the face of said plate opposite to that from which said sleeve extends, and having an opening in alignment with the bore of said sleeve, a spike plate engaging the other face of said washer and having an opening in alignment with the said opening in said cushion, and a spike having a shank extending through said aligned openings in the bore of said sleeve, and carrying a spike element projecting below said spike plate.

4. A spike for a golf shoe comprising, in combination: a main plate having means for securing the same to the sole of a golf shoe, a spike plate carrying a spike element, and a rubber cushion interposed between and permanently bonded to said plates.

5. A spike for a golf shoe comprising, in combination: a main plate having means for securing the same to the sole of a golf shoe, a spike plate carrying a spike element, a rubber cushion interposed between said plates, and peripheral means for maintaining said plates and cushion in assembled relation.

6. A spike for a golf shoe comprising, in combination: a main plate having means for securing the same to the sole of a golf shoe, a spike plate carrying a spike element, a rubber cushion interposed between said plates, and fingers carried by said main plate at the periphery thereof, and extending downwardly over the edges of said cushion and spike plate to which they are interlocked by inturned flanges.
